(57) **CLAIM**

The ornamental design for a table, as shown and described.

DESCRIPTION

FIG. 1 is a perspective view of the table according to my new design;

FIG. 2 is a perspective view thereof taken from a vantage point different from that of FIG. 1;

FIG. 3 is a perspective view of the underside of the table;

FIG. 4 is a short-side elevational view thereof, the other short-side elevational view being identical to that of FIG. 4;

FIG. 5 is a long-side elevational view thereof, the other long-side elevational view being identical to that of FIG. 5;

FIG. 6 is a plan view thereof taken from above; and,

FIG. 7 is a plan view of the table taken from below.
